UNITED STATES PATENT OFFICE.

GEORGE F. EBERHARD, OF CLEVELAND, OHIO.

DESIGN FOR A CLIP-COCKEYE.

SPECIFICATION forming part of Design No. 14,374, dated October 30, 1883.

Application filed July 30, 1883. Term of patent 7 years.

To all whom it may concern:

Be it known that I, GEORGE F. EBERHARD, a citizen of the United States, residing at the city of Cleveland, in the county of Cuyahoga and State of Ohio, have invented and produced a new and original Design for Clip-Cockeyes, of which the following is a specification, reference being had to the accompanying engravings, forming a part thereof.

10 Figure 1 is a front elevation of my newly-designed clip-cockeye; and Fig. 2 is a similar view, representing the clip-cockeye attached to the trace and sufficiently narrow to avoid covering the trace-stitching.

15 The leading features of my design consist in the front part of the clip having each of its side edges curved in substantially the form of a printer's brace, with the central points of the braces inward or toward each other, the

end or part beyond the braces being an arc of 20 a circle. The contour of nearly the whole of each side edge of the front or ornamental part, *a*, of the clip-cockeye is in a curved form, resembling a printer's brace, *c*, with the central points, *c c*, toward each other. The end *s* of 25 the clip between the extremities of the braces is in the form of an arc.

I claim as my invention—

The design for a clip-cockeye herein shown and described, the same consisting of the front 30 part, *a*, having the main contour of each side edge in a curved form, resembling a printer's brace, with the central points, *c c*, inward or toward each other.

GEORGE F. EBERHARD.
